L. MARX

FIGURE TOY

Filed Dec. 19, 1923

Patented July 8, 1924.

1,500,590

UNITED STATES PATENT OFFICE.

LOUIS MARX, OF NEW YORK, N. Y.

FIGURE TOY.

Application filed December 19, 1923. Serial No. 681,611.

To all whom it may concern:

Be it known that I, LOUIS MARX, a citizen of the United States, and resident of New York city, in the county of New York and State of New York, have invented certain new and useful Improvements in Figure Toys, of which the following is a specification.

This invention relates to a figure toy, and more particularly to a mechanically operated figure toy made in representation of a fowl such as a chicken or goose; and has special reference to the provision of a toy fowl adapted to be set into operation for simulating a food seeking or consuming activity.

A principal object of my present invention comprehends the provision of a mechanically operated toy fowl constructed and designed so that when energized the body of the fowl will be moved to and from the ground or like support in life-like resemblance to the food pecking action of the fowl.

A further principal object of the present invention includes the provision of a toy of this character which is designed and constructed so that when operated the food pecking action of the toy is combined with a propulsion of the toy along a support so as to enhance the effect and more closely simulate the natural behaviour of the fowl when seeking or consuming food.

To the accomplishment of the foregoing and such other objects as may hereinafter appear, my invention consists in the elements and their relation one to the other as hereinafter particularly described and sought to be defined in the claims; reference being had to the accompanying drawings which show a preferred embodiment of my invention and in which:

Fig. 1 is a perspective view of the figure toy of my invention,

Fig. 2 is a central longitudinal cross-sectional view thereof showing the different positions of the toy when in action, and

Fig. 3 is a view taken in cross-section on the line 3—3, Fig. 2.

Referring now more in detail to the drawings, the toy fowl comprises a body member 10 mounted for oscillating movement on the plurality of leg members 11 and 12 and a motor mechanism generally designated as 13 for mechanically operating

the toy for effecting the oscillation of the body between a substantially horizontal or normal body position, as shown in full lines in Fig. 2, to a downwardly inclined or food pecking position as shown in dotted lines in said figure, and for effecting the simultaneous propulsion of the toy along the ground or other support such as 14.

The body 10 may for convenience of construction comprise the body members 10' and 10² shaped and designed so as to represent a species of fowl such as a chicken or goose, the body members being preferably formed of sheet metal concaved to produce the hollow body shown in the drawings, the said body members being joined or secured together in any approved manner.

For oscillatably mounting the body on the leg members, the body is provided with the bottom plate 15 to which it is secured by means of tongue elements (not shown) integrally formed with the body members received by the spaced slots 16, 16 in the plate 15, the plate being provided with the upturned members 17, 17 forming spaced bearings for a rod 18. To the opposite ends of the rod 18 are fixedly attached the leg members 11 and 12, each of which includes an elongated foot portion 19 adapted to properly support the toy upon the ground.

For effecting the food pecking action of the toy and for simultaneously propelling the same along the ground, I provide the motor mechanism 13 heretofore referred to carried by the body and connected to the leg members constructed so that when set into operation the body 10 will be moved between the positions indicated in Fig. 2; and in the preferred construction the motor mechanism 13 is such that the body is moved downwardly with a relatively slow motion and is returned upwardly with a quick and resilient motion, with the action such as to produce a forward "hopping" and propelling movement of the toy.

The motor mechanism 13 more specifically comprises a torsion spring 20, the outer end of which is anchored to an inverted U-shaped support 21 fixed to the plate 15, the inner end of said spring being attached to a winding shaft 22 journaled in the plate 15 and support 21 and provided with a winding key 23. Fixed to the shaft 22 there is provided the disk ratchet member 24

having the spaced ratchet teeth 25 adapted to ride over and engage orifices 26 in a gear 27, the said gear being loose on the shaft 22 and being arranged to mesh with 5 a pinion 28 fixed to a shaft 29 which is also journaled in the plate 15 and the support 21. The pinion shaft 29 carries a crank arm 30 to which is connected one end of a link element 31, the other end of 10 the link element being connected to a rod 32 fixed at opposite ends to upwardly extending arms 33 and 34 which are preferably formed integrally with the leg members 11 and 12 respectively. With this construction it will be evident that when the 15 spring 20 is energized, energy may be transmitted from the gear 27 to the leg members to effect the to and fro rocking motion of the body relatively to the leg members. 20 For producing the desired activity, there is also provided the resistant element 35 in the form of a tension spring connected at one end, as at 36, to the rod 32 and connected at its other end, as at 37, to a finger 25 38 which may be formed integrally with the support 21. This resistant member functions to oppose the movement of the link member 31 during the movement of the body 10 from its normal to the downwardly inclined position and to aid the return 30 movement thereof. As will be seen from a consideration of Figs. 2 and 3 of the drawings, when the toy is placed on the ground or other support 14, the body 35 of the toy under the influence of gravity and the action of the torsion spring 20 will move downwardly in opposition to the resistant spring 35, this producing a relatively slow downward movement of the body. The parts are so proportioned that 40 when the beak of the fowl contacts with or is adjacent to the support 14 as shown in dotted lines in Fig. 2, the link element 31 and the crank arm 30 are in alinement; and it will be evident that as the crank arm 30 passes the dead center position, the 45 resistant element 35 will change from opposing to aiding the motor spring 20, the combined actions of these spring parts being such that the body 10 is returned to its normal body position with what may be described as a quick jerk or snap, producing a "hopping" and energetic propulsion of the toy along the support. 50 The use and operation of my figure toy will in the main be fully apparent from the above detailed description thereof. It will be further apparent that numerous changes may be made in the operating mechanism of 55 the toy, as well as in the shape and appearance of the same; and other operating and propelling mechanisms may be employed for producing the desired action, the essence of the invention residing in the provision 60 of the toy fowl characterized by its being 65

mechanically moved in striking simulation of a pecking food seeking or food consuming activity.

I claim:

1. A toy fowl comprising a body member formed in representation of a fowl, a plurality of leg members, the said body member being mounted on the leg members for oscillating movement thereon between a substantially horizontal or normal body position and a downwardly inclined position with the beak of the fowl adjacent a support such as the ground on which the toy is placed, and mechanism carried by the body member and connected to the leg members for oscillating the body member relatively to the leg members in simulation of an eating or pecking action. 70
2. A toy fowl comprising a body member formed in representation of a fowl, a plurality of leg members, the said body member being mounted on the leg members for oscillating movement thereon between a substantially horizontal or normal body position and a downwardly inclined position with the beak of the fowl adjacent a support such as the ground on which the toy is placed, and mechanism carried by the body member and connected to the leg members for oscillating the body member relatively to the leg members in simulation of an eating or pecking action. 80
3. A toy fowl comprising a body member formed in representation of a fowl, a pair of leg members, the said body member being mounted on the leg members for oscillating movement thereon between a substantially horizontal or normal body position and a downwardly inclined position with the beak of the fowl adjacent a support such as the ground on which the toy is placed, motor mechanism carried by the body member, a link element connecting the motor mechanism with the leg members to effect the oscillation of the body member upon operation of the motor mechanism, and a resistant element connecting the motor mechanism with the leg members operative so as to oppose the downward motion of the body member to produce a relatively slow movement thereof, and to aid the upward return motion of the body member to produce a relatively quick return movement thereof, whereby the toy when operated is propelled along the support and is moved in simulation of an eating or pecking action. 90
4. A toy fowl comprising a body member formed in representation of a fowl, a plurality of leg members having elongated foot portions for supporting the body member for propulsion along a support such as the 100

ground, the said body member being mounted for oscillation on the leg members between substantially horizontal and downwardly inclined positions, these positions corresponding respectively to the normal body position and with the food pecking position of the fowl, a spring motor mechanism carried by and housed within the body member, a link element connecting the 10 motor mechanism with the leg members for producing the oscillating movement of the body on operation of the motor mechanism, and a resistant element connecting the motor mechanism with the leg members operative

so as to oppose the gravitational movement 15 of the body member when the toy is placed upon a support to produce a relatively slow downward motion of the body and operative to aid the spring motor mechanism to produce a quick upward return movement 20 of the body whereby the toy is propelled along the support when operated and is moved in simulation of an eating or pecking action.

Signed at New York city, in the county 25 of New York and State of New York, this 18th day of December, A. D. 1923.

LOUIS MARX.
